UNITED STATES PATENT OFFICE.

WILLIAM B. HAUTER, OF MORTON, ILLINOIS, ASSIGNOR TO A. F. MEYER MFG. CO., OF MORTON, ILLINOIS, A CORPORATION OF ILLINOIS.

GRAIN ELEVATOR.

Application filed September 26, 1919. Serial No. 326,449.

To all whom it may concern:

Be it known that I, WILLIAM B. HAUTER, a citizen of the United States, a resident of Morton, in the county of Tazewell and State 5 of Illinois, have invented new and useful Improvements in Grain Elevators, of which the following is a specification.

This invention has reference to elevators, and relates particularly to elevators used in cribs on the farm for the storage of corn and grain of all sorts.

One of the objects of the present invention is to improve the elevating mechanism, in the types of elevators referred to, by employing 15 a roller chain for moving the buckets, or similar conveying means, and constructing the elevator structure to permit the use of such a chain.

The invention has for a further object, to 20 do away entirely with the use of sprocket wheels in the elevator boot, made possible by the use of a roller chain, and to provide a curved guide or guides for the chain, thereby relieving the friction usually centered on the 25 shaft carrying the sprockets and distributing such friction to each of the rollers in the chain, at this point.

That my invention, may be fully understood, reference is had to the following drawings, in which:

Figure 1 is a side elevation, partly in section, showing a preferred form of elevator with my invention applied thereto;

Figure 2 is an end elevation, partly in section, of the elevator, with improvements seen in Figure 1;

Figure 3 is a detail showing a part of the chain and part of a bucket attached;

Figure 4 is a cross-section in plan, as the 40 same would appear if taken on the line 4—4 of Figure 1;

Figure 5 is an enlarged side elevation of one of the corner constructions for the boot;

Figure 6 is a plan of Figure 5, partly in 45 section;

Figure 7 is an end elevation, partly in section, of Figure 5, and

Figure 8 is a cross-section on the line 8—8 of Figure 5.

Like characters of reference denote corresponding parts throughout the figures.

In the drawings, I have illustrated the preferred form in which the invention should be used, i. e., an elevator to be used

inside of a crib, the lifting leg to be placed on 55 one side of the driveway through the crib; the return leg to be placed on the opposite side of said driveway; the receiving boot located beneath the floor of the driveway; communication being had therewith through a trap in 60 the driveway floor, and the head or discharge end of the elevator being located at a distance above the floor of the driveway and preferably centrally thereof and having a receiving hopper to which may be connected 65 any well known form of swiveled, extensible and flexible discharge spout to convey the elevated material to the several bins of the cribs.

One form of an inside elevator, such as I 70 have referred to, is shown in the patent to Meyer, dated May 4, 1909, and numbered 920,602.

1 designates the floor of the driveway through the crib and below which, in a well-portion 2, the boot 3 of the elevator is located, extending transversely thereof, and at its opposite ends there are connected to, and uprise therefrom, the elevator legs 4 and 5. The leg 4 serves to guide the lifting run of 75 the elevator chains 6, and the leg 5 serves to guide the descending run of such chains. The upper ends of the legs 4 and 5, are connected by the transversely disposed head 7 from which depends the preferably cen- 80 trally located hopper 8.

The chains 6 comprise the links 9 and 10, connected with the rollers 11. The links 9 are preferably straight links and one section of each link 10 is formed with the off-set body 12, to which are secured the cups 13. 85

Each leg 4 and 5 of the elevator comprise the opposite parallel pairs of upstanding beams 14. The beams of each pair are spaced a suitable distance apart to form the 90 guide-way 15 in which travel the chains 6. The rollers 11 travel on the facing edge of the beams 14, as shown. The cups 13 travel up and down the legs 4 and 5 between the 95 opposite pairs of beams, as shown.

Journaled in the head at the upper edge of the leg 4, are sprocket wheels 16 and also journaled in the head at the upper end of the leg 5, are sprocket wheels 17. The sprocket chains 6 travel over these respective 100 wheels when leaving the leg 4 and entering the leg 5. The sprocket wheel 4 is also located, preferably higher than the sprocket 105

- wheel 5, whereby the cups 10 are tilted whole boot structure is usually built in slightly as they leave the sprocket wheel 16, cement. thereby insuring the discharge of the material into the hopper 8. Although not 5 shown, there is preferably connected to the lower end of the hopper, an extensible, flexible and swinging spout to direct the material to the different bins of the crib, not shown.
- 10 Ordinarily at each end of the boot 2, there are sprocket wheels to guide the chains 6 from the leg 5 and to the leg 4, and with such a structure with the accompanying shafts, all the friction is centered on the 15 shafts carrying such sprocket wheels. I have done away with this structure and to guide the roller chains 6, I provide the corner or end members 18, arranged in pairs at each end of the boot and spaced apart to 20 receive the chains, and between which travel the cups 13, which move along the bottom of the boot, and scoop up the material to be elevated. These members 18 are substantial duplicates of each other, therefore, the description of one will suffice for all. 25
- The member 18 is preferably a casting, but may be stamped out of sheet metal if desired. It is in the form of a plate having the horizontal and vertical angular edges 30 19 and 20 and with the curved end 21. In the body of the plate is provided the curved chain guiding groove 22 formed with the upper and lower roller bearing surfaces 23 and 24, and the outer protecting wall 25. 35 The edge 20 of the plate is also formed with the off-set wall 26, preferably flush with the wall 25 of the guiding groove 22.
- The members 18 are set in each end of the boot and a sheet metal shield 27 is laid along 40 the bottom of the boot, and turned up at the ends to conform to the curved ends 21 of the plates 18 and secured thereto. The lower ends of the beams 14 of each leg are secured to these members 18, by being off-set, as at 28, so as to be bolted or otherwise 45 suitably secured to said plates. Extending between and secured to the off-set wall portions 26 of the respective end plates 18, are pairs of horizontally disposed beams 29, 50 spaced apart to provide chain guides or grooves 30, which communicate with and form continuations of the grooves 22 in the plates 18 and the grooves or guides 15 between the pairs of upstanding beams 14. 55 Thus it will be seen that the chains 6 travel in the guides or grooves 30 between the beams 29 and the guides or grooves 22 in the end plates 18, when leaving and entering the boot 2, and the friction at the ends of the 60 boot is distributed to all the rollers 11 of the chains, as they travel through the boot. This structure is not only much more simple and compact than the sprocket wheel structure, but is much more efficient and less 65 likely to give trouble, inasmuch as the
- What I claim is:
1. In a grain elevator, in combination, conveying and elevating means including 70 chains and cups, runs for the said chains and cups comprising vertically disposed spaced beams forming chain guides, a discharge head, sprocket wheels journaled in the head to guide the chains, a receiving 75 boot, chain guides for the opposite corners of the boot comprising spaced plates formed with inwardly facing curved guiding grooves to direct the chains to and from the boot, and elevating chains having rollers 80 adapted to travel on the bearing surfaces of the matching faces of the beams, and on the bearing surfaces of the guides in said plates. 85
  2. In a grain elevator, in combination, a boot arranged below the floor in the drive-way of a crib, a discharge head at an elevated position above the floor of the drive-way, sprocket wheels journaled in the head to guide the chains, lifting and return legs arranged on opposite sides of the drive-way, 90 their upper and lower ends, respectively, connecting head and boot and comprising vertically disposed spaced beams forming chain guides, chain guiding plates at opposite corners of the boot and formed with inwardly facing curved chain guiding grooves to direct the chain to and from the boot, chain guides in the boot connecting said plates, roller chains, and cups connecting said chains at intervals. 95
  3. In a grain elevator, in combination, the head, boot, legs connecting the head and boot, sprocket wheels journaled in the head to guide the chains, guides for the chains in the opposite corners of the boot comprising spaced plates each formed with inwardly facing curved guiding grooves, and roller chains movable through said guiding plates, legs and over said sprocket wheel. 100
  4. In a grain elevator, in combination, a boot, legs connecting the boot at opposite ends, conveying chains traversing said boot and legs, guides for the chains where the legs and boot unite, said guides comprising spaced plates each formed with correspond- 105 ing inwardly facing curved guiding grooves. 110
  5. In a grain elevator, in combination, a boot, legs connecting the boot at opposite ends, conveying chains traversing said boot and legs, guides for the chains where the legs and boot unite, each guide comprising a corner plate having two straight edges and a curved edge and formed with a curved guiding groove in its side face opening out of said straight edges, said groove 115 120 enclosed on three sides. 125
  6. In a grain elevator, in combination, a boot, a chain guide for the boot comprising plates having two straight edges and a curved edge and formed with curved guid- 130

ing grooves in their side faces opening out of said straight edges, a vertical leg comprising beams having their lower ends connected with said plates, and spaced apart 5 to form chain guides communicating with the grooves in said plates, and horizontally arranged beams in said boot connected with said plates and spaced apart to form chain guides connecting with the grooves in said 10 plates.

7. In a grain elevator, in combination, a boot, legs connecting the boot at opposite ends, conveying chains traversing said boot and legs, guides for the chains where the 15 legs and boot unite, each guide comprising

a plate formed with a curved guiding groove in its face and closed on three sides.

8. In a grain elevator, in combination, a boot, legs connecting the boot at opposite ends, conveying chains traversing said boot 20 and legs, guides for the chains where the legs and boot unite, each guide formed with a curved guiding groove in its side face and closed on three sides, and an off-set on one edge of the plate flush with one wall of said 25 groove.

In witness whereof, I have hereunto affixed my hand this 10th day of September, 1919.

WILLIAM B. HAUTER.
